ANTENNA SYSTEMS

Floyd T. Wimberly, Watertown, Mass., assignor to Raytheon Manufacturing Company, Newton, Mass., a corporation of Delaware

Application June 25, 1952, Serial No. 295,423

16 Claims. (Cl. 343—100)

This invention relates to systems for radiating and receiving electrical energy, and more particularly to an antenna system useful for radar purposes.

In radar systems of the frequency-modulated or continuous-wave type, a portion of the transmitted signal is fed directly into the receiver to beat with the returning echo wave, thereby producing a signal indicative of range or speed according to well-known practice.

Prior to this invention it has been difficult to adequately isolate the transmitting wave from the receiving wave so that only a small amount of the transmitted wave was fed directly to the receiver. This invention discloses an antenna system wherein the transmitting antenna is isolated from the receiving antenna to a greater degree than was heretofore possible. Briefly, this is accomplished by using radiating horns whose large ends are connected to a ground plane. The radiation patterns of the horns are oriented in a direction perpendicular to the ground plane, and the apertures in the ground plane with which the large ends of the horns register are spaced apart by a plurality of wave lengths.

This invention further discloses an antenna structure which is structurally rigid whereby microphonics, which would cause modulation of the portion of the signals fed from the transmitting antenna to the receiving antenna, are substantially eliminated. Briefly, this is accomplished by rigidly attaching the horns to the ground plane, and by connecting a rigid member between the horns at a point remote from the ground plane. More specifically, the rigid member is connected to the horns at the points of coupling of the horns to the signal translation means by which the transmitted signal is coupled into the transmitting horn and the received signal is picked up from the receiving horn. In order to insure a predetermined amount of signal energy being fed directly from the transmitting horn to the receiving horn, a signal channel is coupled from the transmitting horn to the receiving horn. In order to insure rigidity of this coupling path to prevent modulation of this energy, the channel is made part of the rigid member, more specifically being a coaxial line inside the rigid member, said coaxial line having a filling of lossy material whereby the desired degree of attenuation of the signal fed directly from the transmitting horn to the receiving horn may be accurately maintained.

This invention further discloses a system wherein all the high-frequency energy channels are positioned in one unit, thereby eliminating the need for high-frequency cables to connect one unit with another, or the use of flexible or rotating high-frequency joints to allow the movement of one unit with respect to another. Specifically, the high-frequency unit is the antenna system with the source of high-frequency energy, for example, a magnetron, resiliently mounted on the antenna unit. The receiver mixer is also mounted on the antenna unit such that the output of the receiver, which is a relatively low frequency intelligence signal, may be conducted from the

2

antenna to any other unit, for example, an indicator unit, by means of conventional wiring techniques.

Other and further objects and advantages of this invention will be apparent as the description thereof progresses, reference being had to the accompanying drawings, wherein:

Fig. 1 illustrates a partially broken-away perspective view of an antenna system embodying this invention;

Fig. 2 illustrates a front elevation view of the device shown in Fig. 1;

Fig. 3 illustrates a longitudinal cross-sectional view of the device shown in Figs. 1 and 2 taken along line 3—3 of Fig. 2;

Fig. 4 illustrates an enlarged view of a detail of the device shown in Figs. 1, 2, and 3;

Fig. 5 illustrates a block diagram of a frequency-modulation or Doppler radar system embodying the antenna system of this invention;

Fig. 6 illustrates a block diagram of a pulse echo radar system embodying the antenna system of this invention; and

Fig. 7 illustrates an installation of the antenna system of this invention adapted for rotation about a vertical axis as would be required for a conventional marine navigational radar system.

Referring now to Figs. 1, 2, and 3, there is illustrated a ground plane 10 comprising a flat metallic member. Rigidly connected to the ground plane 10 is a pair of wave guide horns 11 and 12, respectively. Horns 11 and 12 have their large ends flared in a direction perpendicular to a line intersecting and perpendicular to the longitudinal axes of the horns, said longitudinal axes being oriented in a direction perpendicular to the ground plane 10. By this structure, the horns 11 and 12 are substantially matched to the free space occurring outside the horns when the horns are excited in the TE₀₁ mode with the electrostatic lines perpendicular to the plane containing the axes of the horns.

The horn 12 is used as a transmitter horn and is excited by a probe 13 extending into the horn at a point in the region adjacent the small end of the horn which is closed by a conductive plate as at 14. The probe 13 is positioned parallel to the electrostatic lines of the waves in the guide 12, but does not extend entirely across the guide 12.

The probe 13 is surrounded by a sheath 15 of dielectric material which extends entirely across the guide and out through one wall thereof surrounding the probe 13. Where the sheath 15 and probe 13 extend out through the wall of the guide 12, they are attached to a conventional coaxial line fitting 16, whereby power is fed into the horn 13. The axis of probe 13 does not intersect the axis of the horn but is offset, by an amount determined by the impedance of the coaxial line coupled to the probe, to produce a good impedance match between the coaxial line and the horn. Similarly, the probe 13 is spaced from the shorting member 14, closing the small end of the guide 13, for impedance matching purposes.

A coaxial line illustrated diagrammatically at 17 connects the coaxial fitting coupled to probe 13 with the coaxial output 18 of a magnetron oscillator 19 which is resiliently mounted in the space between the horns 11 and 12. The magnetron 19 is shown by way of example only and any desired source of high-frequency energy, such as a klystron or high-frequency vacuum tube triode oscillator, could be used. As is illustrated here, the magnetron 19 is rigidly clamped to a support member 20 by means of straps 21. A connecting plug 22 is attached to support member 20 so that the magnetron 19 may be readily removed from the device by simply disconnecting the coaxial coupling 18, removing the straps 21, and pulling the magnetron 19 out of the plug 22. All of the desired low frequency electrical connections to the magnetron

60

65

66

70

19, such as heater voltages and plate voltage, are fed to the magnetron 19 through the plug 22.

Other components may also be mounted on the member 20, such as the transformer 23, which may be used to supply anode voltage to the magnetron 19. In addition, such items as resistors or condensers, illustrated for example at 24, may be appropriately connected to terminals 25 attached to the member 20.

The support member 20 is resiliently attached to the horns 11 and 12 and the ground plane 10 by means of shock mounts 26 which may be of any desired type. The shock mounts, shown here by way of example only, comprise rods 27 rigidly connected to the support member 20 and bonded to rubber diaphragm members 29 positioned in and bonded to metallic cups 30. The metallic cups 30 are, in turn, bolted by means of bolts 31 to brackets 32 attached to the horns 11 and 12 and to the ground plane 10.

The horn 11 is similar to the horn 12 but is used as a receiving antenna. Consequently, there is no coaxial line coupling the magnetron 19 with the receiving horn 11. Instead, there is illustrated herein a balanced mixer utilizing a pair of crystal rectifiers 33 positioned in holders 34, extending into the sides of the receiver horn 11. This mixer section, which may be of any desired well-known type, beats the portion of the signal fed directly from the transmitter horn 12 to the receiver horn 11, in a manner to be described presently, with reflected echo signals to produce an output signal having a low frequency component, said component being fed over conventional wiring 35 to any desired utilization circuit, such as an indicator. The crystals are fed out of phase by the echo signals received by the horn 11, and in phase by the portion of the signal from horn 12. The details of the mixer section are more completely described in copending application, Serial No. 212,932, filed February 27, 1951, by Jenks et al, now Patent No. 2,713,636, dated July 19, 1955.

In order to feed the desired portion of the transmitted signal directly from the transmitting horn 12 to the receiving horn 11, there is provided a coaxial line having a central conductor 36. One end of conductor 36 is connected to a coupling loop 37 extending into transmitter horn 12 through an aperture in the shorting plate 14 at the rear of horn 12. An insulating bushing 38 is provided around the portion of loop 37 which passes through the shorting plate 14 to insulate member 37 from the shorting plate at this point. The end of the loop 37 inside the horn 12 is connected to one wall of the horn 12.

The other end of conductor 36 extends into the horn 11 through an aperture in a shorting plate 39 at the small end of horn 11 and is connected to the mixer 34 in horn 11. The conductor 36 has a portion thereof surrounded by a layer of lossy material, as at 40, to attenuate the signal passing from the transmitting horn through the coaxial line, whose central conductor is 36, to the receiving horn 11. The outer conductor of the coaxial line whose inner conductor is 36 comprises a rigid member made in two parts to facilitate assembly of the device. The first or lower half 41 of the outer conductor is rigidly attached to the horns 11 and 12. The second half 42 or cover is screwed, for example, by screws 43, to the member 41, thereby producing a completely rigid coaxial line assembly connecting the transmitter horn 12 with the receiving horn 11.

The large ends of the horns 11 and 12 are rigidly attached to the ground plane 10 which has sufficient thickness to prevent any relative movement between the large ends of the horns. The members 41 and 42 are also sufficiently rigid to prevent any relative motion between the small ends of the horns. Thus it may be seen that the transmitting and receiving horn structure is a rigid unit, thereby eliminating possibility of spurious signals due to variation of the distance between the receiving and transmitting horns.

In order to prevent dust and other material from entering the horns 11 and 12, the large ends of the horns are closed by a plate of dielectric material as at 44. The dielectric material 44 may be of any desired type which is permeable by radiated energy and the thickness of the member 44 is made such as to provide the best impedance match between the horns and the free space. For example, it has been found that for the particular horn configuration illustrated, good results may be obtained with a member 44 which is approximately six-tenths of a wave length thick at the desired operating wave length of the system.

There is provided a cover 45 surrounding the horns and associated structure and engaging the ground plane 10. The cover 45 comprises a pressed metal covering member 46 which is attached, for example, by riveting or spot welding, to a ring 47 surrounding the horns adjacent the ground plane 10. The ring 47 which may be, for example, a casting, has a slot 48 therein whose depth is made on the order of a half wave length when the cover is attached to the ground plane 10. The slot 48 is filled with a dust-protective medium, such as cork, and the wall portion 49 of the slot 48, which is positioned nearest the ground plane 10, has a cork washer 50 positioned in substantial contact with said wall portion and the ground plane 10. The ground plane 10 is attached to the ring 47 by means of screws 51 extending through the ground plane 10 and threadedly engaging a nut 51a attached to ring 47. The portion of the ring 47, which surrounds the ground plane 10, is spaced therefrom by a portion of the slot 48, and is attached to the support structure, for example, the skin 52 of an airplane, by means of rivets 53. Since the slot 48 is substantially a half wave length deep, the bottom of the slot, which is shorted by the member 47, reflects a short circuit to the exterior face of the system comprising the skin 52 and the exposed surface of the ground plane 10. Since the ground plane 10 is an appreciable portion of a quarter wave length thick, the junction of ground plane 10 with the lip portion 49 will be at a relatively high impedance point along the slot 48. Accordingly, any looseness of the screws 51 will not cause a static condition to be generated by vibration of the ground plane and horn structure with respect to the ring member 47.

Referring now to Fig. 5, there is shown a block diagram of a frequency-modulated or Doppler radar device embodying the antenna system illustrated in Figs. 1, 2, and 3. There is shown schematically within the antenna system unit, indicated by the components within the box 54, transmitting and receiving horns 12 and 11 connected to a ground plane 10. The transmitting horn 12 is fed energy from a transmitter 55, which may be, for example, the magnetron 19, through a line 56 which consists of the necessary wave guide or coaxial line structure. The energy is radiated from the horn 12, as at 57, and upon impinging on remote objects is reflected back to the horn 11 as at 58. A small portion of energy is also fed directly from the horn 12 to the mixer receiver section 59 attached to the horn 11 through line 60 which may comprise, for example, the members 36, 40, 41, and 42, illustrated in Figs. 1 through 3.

The mixer receiver section 59 may be, for example, a balanced crystal mixer, as illustrated in Fig. 1. The output of the mixer receiver section 59 is an audio frequency which is fed by means of conventional wiring 61 to an indicator 62, such as a meter or cathode ray tube. A power supply 63 is provided for supplying power to the transmitter and the indicator by means of conventional wiring.

Referring now to Fig. 6, there is shown a modification of the system illustrated in Fig. 4 to allow use of the system with a pulse echo radar system. The system is similar to that shown in Fig. 5 except that the transmitter 55 is pulsed instead of being a continuous wave transmitter. There is no line 60 connecting the trans-

mitter horn with the receiver horn but rather a local oscillator 64 is provided for supplying a mixing signal to the mixer receiver section 59. Also, a synchronizing pulse is fed from the transmitter 55 to the indicator 62, by means of a line 65, to synchronize the indicating device 62, for example, the initiation of the sweep of a cathode ray tube with the emission of a pulse of high-frequency energy from the transmitter 55.

Referring now to Fig. 7, there is shown diagrammatically an installation of the antenna system 54 in a radar system, such as a marine navigational radar, wherein the antenna system is adapted to rotate about a vertical axis. The antenna system 54 is fastened to a cylindrical support member 66, for example, in the same manner that it is illustrated as being fastened to the skin 52 of the airplane in Figs. 1 through 4. The cylinder 66 has the axis thereof positioned vertically and is attached to a shaft 67 which rotates the cylinder 66 about its axis, thereby causing the antenna system 54 to scan in a horizontal direction about the vertical axis. The shaft 67 is supported by a gear box 68 through which a motor 69 drives the shaft 67 by means of gears which are not illustrated.

This completes the description of the embodiments of the invention illustrated herein. However, many modifications thereof may be made without departing from the spirit and scope of this invention. For example, a particular mounting of the antenna unit with respect to the support structure is shown by way of example only, and any desired mounting structure could be used. The crystal mixer structure and the probe for coupling the energy into the transmitting horn could have other well-known devices and structures substituted therefor. Accordingly, it is desired that this invention be not limited by the particular details of the embodiments illustrated herein except as defined by the appended claims:

What is claimed is:

1. An antenna system comprising a plurality of fixed wave guides, one end of each of said wave guides registering with a separate aperture in a ground plane and the other end of each of said wave guides being fixedly coupled to respectively different signal translation means, said apertures being spaced along said ground plane by a plurality of wave lengths at the operating frequency range of said system.

2. An antenna system comprising a plurality of fixed wave guides, a ground plane, one end of each of said wave guides registering with a separate aperture in said ground plane and the other end of each of said wave guides being fixedly coupled to separate signal translation means, and a rigid member connected between said wave guides substantially at the points of coupling to said signal translation means.

3. An antenna system comprising a plurality of fixed wave guides, a ground plane, one end of each of said wave guides registering with a separate aperture in said ground plane and the other end of each of said wave guides being fixedly coupled to separate signal translation means, a source of signals mounted between said wave guides and fixedly coupled to one of said wave guides through one of said signal translation means, said apertures being spaced along said ground plane by a plurality of wave lengths at the operating frequency range of said system, and a rigid member connected between said wave guides substantially at the points of coupling to said signal translation means.

4. An antenna system comprising a plurality of fixed wave guides, a ground plane, one end of each of said wave guides registering with a separate aperture in said ground plane and the other end of each of said wave guides being fixedly coupled to respectively different signal translation means, and a rigid member connected between said wave guides at points remote from said ground plane, said rigid member comprising a signal translation channel between said wave guides.

5. An antenna system comprising a plurality of fixed wave guides, a ground plane, one end of each of said wave guides registering with a separate aperture in said ground plane and the other end of each of said wave guides being fixedly coupled to separate signal translation means, and a rigid member connected between said wave guides at points remote from said ground plane, said rigid member comprising an attenuating signal translation channel between said wave guides.

6. An antenna system comprising a plurality of fixed wave guides, a ground plane, one end of each of said wave guides containing a solid dielectric and registering with a separate aperture in said ground plane, a surface of said dielectric being substantially flush with said ground plane, and the other end of each of said wave guides being fixedly coupled to respectively different signal translation means, a source of signals mounted between said wave guides and fixedly coupled to one of said wave guides through one of said signal translation means, said apertures being spaced along said ground plane by a plurality of wave lengths at the operating frequency range of said system, and a rigid member connected between said wave guides substantially at the points of coupling to said signal translation means, said rigid member comprising an attenuating signal translation channel between said wave guides.

7. An antenna system comprising a plurality of fixed wave guides, a ground plane, one end of each of said wave guides containing a solid dielectric and registering with a separate aperture in said ground plane and the other end of each of said wave guides being fixedly coupled to separate signal translation means, and a rigid member connected between said wave guides at points remote from said ground plane, said rigid member comprising an attenuating signal translation channel between said wave guides.

8. An antenna system comprising a plurality of fixed energy radiation horns having signal translation means coupled thereto, and means for isolating said horns from each other comprising a ground plane, the large ends of said horns containing a solid dielectric and being rigidly connected to said ground plane, a surface of said dielectric being substantially flush with said ground plane and the other end of each of said horns being fixedly coupled to respectively different signal translation means, a source of signals mounted between said wave guides and fixedly coupled to one of said wave guides through one of said signal translation means, and a rigid member connected between said horns at the small ends thereof, said rigid member comprising an attenuating signal translation channel between said horns.

9. An antenna system comprising a plurality of fixed wave guides, one end of each of said wave guides registering with a separate aperture in a ground plane and the other end of each of said wave guides being fixedly coupled to respectively different signal translation means, said guides being tapered in the regions of registry with said apertures in a direction perpendicular to a line intersecting the axes of said guides and being substantially straight in the region of coupling to said translation means, said apertures being spaced along said ground plane by a plurality of wave lengths at the operating frequency range of said system.

10. An antenna system comprising a plurality of fixed wave guides, a ground plane, one end of each of said wave guides registering with a separate aperture in said ground plane and the other end of each of said wave guides being fixedly coupled to separate signal translation means, said guides being tapered in the regions of registry with said apertures in a direction perpendicular to a line intersecting the axes of said guides and being substantially straight in the region of coupling to said translation means, and a rigid member connected between said wave guides substantially at the points of coupling to said signal translation means.

11. An antenna system comprising a plurality of fixed wave guides, a ground plane, one end of each of said wave guides registering with a separate aperture in said ground plane and the other end of each of said wave guides being coupled to separate signal translation means, said guides being tapered in the regions of registry with said apertures in a direction perpendicular to a line intersecting the axes of said guides and being substantially straight in the region of coupling to said translation means, a source of signals coupled to one of said wave guides through one of said signal translation means, said apertures being spaced along said ground plane by a plurality of wave lengths at the operating frequency range of said system, and a rigid member connected between said wave guides substantially at the points of coupling to said signal translation means.

12. An antenna system comprising a plurality of fixed wave guides, a ground plane, one end of each of said wave guides registering with a separate aperture in said ground plane and the other end of each of said wave guides being fixedly coupled to respectively different signal translation means, said guides being tapered in the region of registry with said apertures in a direction perpendicular to a line intersecting the axes of said guides and being substantially straight in the region of coupling to said translation means, and a rigid member connected between said wave guides at points remote from said ground plane, said rigid member comprising a signal translation channel between said wave guides.

13. An antenna system comprising a plurality of fixed wave guides, a ground plane, one end of each of said wave guides registering with a separate aperture in said ground plane and the other end of each of said wave guides being fixedly coupled to separate signal translation means, said guides being tapered in the regions of registry with said apertures in a direction perpendicular to a line intersecting the axes of said guides and being substantially straight in the region of coupling to said translation means, and a rigid member connected between said wave guides at points remote from said ground plane, said rigid member comprising an attenuating signal translation channel between said wave guides.

14. An antenna system comprising a plurality of fixed wave guides, a ground plane, one end of each of said wave guides containing a solid dielectric impedance matching member registering with a separate aperture in said ground plane, a surface of said dielectric being substantially flush with said ground plane, and the other end of each of said wave guides being coupled to respectively different signal translation means, said guides being tapered in the regions of registry with said apertures in a direction perpendicular to a line intersecting the axes of said guides and being substantially straight in the region of coupling to said translation means, a source

of signals coupled to one of said wave guides through one of said signal translation means, said apertures being spaced along said ground plane by a plurality of wave lengths at the operating frequency range of said system, and a rigid member connected between said wave guides substantially at the points of coupling to said signal translation means, said rigid member comprising an attenuating signal translation channel between said wave guides.

15. An antenna system comprising a plurality of fixed wave guides, a ground plane, one end of each of said wave guides containing a solid dielectric and registering with a separate aperture in a ground plane and the other end of each of said wave guides being fixedly coupled to separate signal translation means, said guides being tapered in the regions of registry with said apertures in a direction perpendicular to a line intersecting the axes of said guides and being substantially straight in the region of coupling to said translation means, and a rigid member connected between said wave guides at points remote from said ground plane, said rigid member comprising an attenuating signal translation channel between said wave guides.

16. An antenna system comprising a plurality of fixed energy radiation horns having signal translation means coupled thereto, and means for isolating said horns from each other comprising a ground plane, the large ends of said horns containing a solid dielectric impedance matching member and being rigidly connected to said ground plane, a surface of said dielectric being substantially flush with said ground plane and the other end of each of said horns being fixedly coupled to respectively different signal translation means, said guides being tapered in the regions of registry with said apertures in a direction perpendicular to a line intersecting the axes of said guides and being substantially straight in the region of coupling to said translation means, a source of signals mounted between said wave guides and fixedly coupled to one of said wave guides through one of said signal translation means, and a rigid member connected between said horns at the small ends thereof, said rigid member comprising an attenuating signal translation channel between said horns.
